UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL RECEPTACLE.

1,328,785.

Specification of Letters Patent. Patented Jan. 20, 1920.

Application filed April 19, 1917. Serial No. 163,291.

To all whom it may concern:

Be it known that I, REUBEN B. BENJAMIN, a citizen of the United States, residing at Chicago, in the county of Cook and State 5 of Illinois, have invented new and useful Improvements in Electrical Receptacles, of which the following is a full, clear, concise, and exact description, reference being had to the accompanying drawing, forming a 10 part of this specification.

My invention relates to electrical receptacles, and, more specifically, to a stand lamp having receptacles for a plurality of lamps and pull switch mechanism for controlling 15 the lamp circuits.

Among the objects of my invention are to provide a device of the character indicated which will be simple in construction, durable and efficient in use, and cheap to 20 manufacture. Further objects will appear from the detailed description to follow and from the appended claims.

In the drawings, in which one embodiment of my invention is shown—

25 Figure 1 is a side elevation of a stand lamp embodying my invention, parts being broken away to show the interior construction;

Fig. 2 is a vertical section on the line 2—2 30 of Fig. 1;

Fig. 3 is a horizontal section on the line 3—3 of Fig. 1 looking in the direction of the arrows;

Fig. 4 is a detail side elevation of part of 35 the shade-support and an associated part;

Fig. 5 is a horizontal section on the line 5—5 of Fig. 2;

Fig. 6 is a vertical section substantially 40 on the line 6—6 of Fig. 5; and

Fig. 7 is a vertical section substantially 45 on the line 7—7 of Fig. 5.

Referring to the drawings in detail, the stand lamp shown comprises a base 10 for resting on any suitable support, a tubular 50 upright pedestal or post 11 secured to the base 10, a plural lamp receptacle 12 supported on the upright 11, and a tubular upright or post 13 extending above the receptacle 12 to which a shade-supporting device 14 is secured.

The plural lamp receptacle 12 comprises an insulating base 15 of porcelain or other suitable material, a plurality of threaded

sheet-metal shell contacts 16 (three in number as shown) for engagement with the corresponding contacts of lamp bases, a conical sheet-metal member 17 forming a center contact means for engagement with the center contacts of the lamp bases, and switch mechanism 18 for controlling the different lamp circuits. The center contact member 17 is electrically connected with the binding-plate 19 on the upper side of the base by means of a screw 20 (Fig. 6) extending through registering openings in the center contact member 17 and the base 15 and threaded into the binding-plate 19, the screw 20 thus serving also to assist in holding the center contact member 17 in place on the base 15. The switch mechanism 18 comprises two rotary make-and-break pull switches 21 and 22, both electrically connected to the binding terminal 23. The switch 21 controls only one of the lamp circuits, while the switch 22 controls the circuits for the other two lamps. Each of these switches 21 and 22 comprises a shaft 24 electrically connected with the binding-plate 28, a switch member 25 (Fig. 7) rotatably mounted on the shaft 24, a spring contact 26 co-operating with the rotatable member 25 to make and break the circuit, a lever 27 oscillatively mounted on the shaft 24, a latchet drive 28 between the lever 27 and the rotatable switch member 25, whereby the oscillations of the lever 27 will cause rotation of the switch member 25, a pull chain 29 connected to the lever 27 to oscillate it in one direction, and a coil torsion spring 30 surrounding the shaft 24 for oscillating the lever in the opposite direction.

The rotatable member 25 comprises an insulating portion 31 and a sheet-metal contact and conductor portion 32 having contacts 33 for engagement with the spring contact 26 and a conducting portion 34 extending between the contact portions 33 and engaging the shaft 24 to electrically connect the contact portions 33 with the shaft. Each shaft 24 is provided with a laterally-extending upturned end 35, and these ends are electrically connected together by means of a sheet-metal strap 36, the ends of which are wrapped around the upturned ends 35. The shaft 24 of the switch 21 is electrically connected with the binding terminal 23 by

means of a sheet-metal strap 37 having a portion wrapped around the end of the shaft. The spring contact 26 of the switch 21 is electrically connected with one of the 5 shell contacts 16 by means of a screw 38 (Fig. 6) extending through an opening in an ear 39 on the shell contact 16 and held in place by means of a nut 40. This screw 38 also serves to assist in holding the shell 10 contact in place.

The spring contact 26 of the switch 22 is electrically connected with the other two threaded shell contacts by means of a screw 41 electrically connecting the spring contact 26 with one of the threaded shells and an arcuate sheet-metal plate 42 (Figs. 3 and 5) electrically connecting the two threaded shell contacts. The screw 38 extends through registering openings in the spring contact 26, insulating base 15, ear 39 of the threaded shell contact, and arcuate plate 42, and is held in place by means of a nut 43. The screw 41 serves to hold one end of the plate 42 in position and assists in holding 25 the threaded shell contact in position. The other end of the plate 42 is held in position by means of a screw 43^a (Figs. 3 and 5) which also extends through the ear 39 of the threaded shell contact to assist in holding 30 this contact in position.

The upper face of the base 15 is provided with pivotal recesses 44, 45, 46 and 47 to receive the binding terminals 19, 23 and the switch mechanisms 21 and 22 and associated parts. A flat insulating cover 48 of fiber or other suitable material is placed over the insulating base 15 to cover the recesses 44, 45, 46 and 47 to house the parts located in said recesses. The insulating 40 base 15 is provided with a central vertical opening 49, into which the post 11 extends and through which the feed wires 50 are led to the binding-screws 51, 52 of the binding-terminals 19, 23.

45 A cup-shaped sheet-metal housing 53 is provided for the lower part of the receptacle 12 for housing the contacts of the receptacle. The insulating base 15 and the cup-shaped housing 53 are prevented from slipping down on the post 11 by means of a supporting sleeve 54 (Figs. 1 and 6) surrounding the post 11, on which the lower central portion of the cup-shaped housing 53 bears. A finishing ring 55 may be interposed between the sleeve 54 and the housing 53, if desired.

To prevent the housing 53 from being bent or sprung, a sleeve 56, of fiber or other suitable insulating material, may be placed 60 around the post 11 between the housing 53 and the insulating base 15. The housing 53 is provided with suitable openings 57 for the pull chains 29. These openings may be formed by cutting out a narrow horizontal 65 strip to form an elongated narrow horizon-

tal opening, and then bending the upper edge of the opening outwardly (as indicated at 58), and the lower edge of the opening inwardly (as indicated at 59) to form smooth guide portions for the pull chains 70 29. By means of this construction, if the pull on the chain is such as to swing it outwardly away from the post 11, the upper lip of the opening will form a smooth curved guide for the chain and if the 75 pull on the chain is such as to swing it in toward the post the lower lip of the opening will form a smooth curved guide for the chains.

The base 15 is held in position on the post 11 by means of a tubular member 60, the lower edge of which bears against a shoulder 61 of the recess 49, the upper end of the post 11 being threaded into the tubular member 60 (Fig. 6). The tubular member 60 and the upper portion of the recess 49 are hexagonal in shape (Fig. 5) so that the tubular member is non-rotatably held in the recess. The tubular member 60 has an opening 62 in one side, through which the feed 90 wires 50 are led to the binding-screws 51, 52 (Fig. 5). An ornamental sheet-metal cap or cover 63 is placed over the insulating base 15 and the insulating cover 48 for housing them. The shade-supporting post 95 13 is threaded into the upper end of the tubular member 60.

The shade-supporting means shown comprise, in addition to the post 13, a sleeve 63^a surrounding the post 13, a sheet-metal centering ring or cup 64 surrounding the post 13 and having a flange resting on the upper edge of the sleeve 63^a a supporting plate 65 bearing on the sleeve 63^a, a plurality of radially-extending arms 66 secured to the 105 supporting plate 65, a ring 67 supported by the arms 66, to which an ornamental shade of cloth or other suitable material may be secured, and a nut 68 threaded on the upper end of the post 13 for holding the parts 110 in assembled position. The lower edge of the sleeve 63^a rests on the cap 63 and holds it in position. The cap 63 bears against the upper edge of the tubular member 60, whereby the cap is prevented from being bent. 115

For convenience in handling and to give it a finished appearance, the nut 68 is provided with a cup-shaped sheet-metal cap 69 having its lower edge flanged over (as indicated at 70) beneath the nut 68 and having 120 an annular, inwardly-extending bead 71 above the nut for holding it in position.

When the lamp is wired, the center contact device 17 is connected with one of the feed wires 50 through the screw 20 and binding terminal 19. The threaded shell contacts of the receptacles are electrically connected with the appropriate feed wire only when the switches 21, 22 are in the proper position to connect them. One of the 130

threaded shell contacts is always electrically connected with the spring contact 26 of the switch 21 through the screw 38, and the other two threaded shell contacts are always 5 electrically connected with the spring contact 26 of the switch 22 through the screw 41 and arcuate plate 42. The contact portions 33 of the switch 21 are always in electrical connection with the binding terminal 10 23 through the conductor portion 34, shaft 24, and sheet-metal member 37. The contact members 33 of the switch 22 are always electrically connected with the binding terminal 23 through the conducting member 15 34 and shaft 24 of the switch 22, through the sheet-metal strap 36 and the shaft 24 of the switch 21, and through the sheet-metal strap 37 to the binding terminal 23. Accordingly, when the switch member 25 of the switch 21 20 is rotated it alternately makes and breaks the circuit to one of the lamps, and when the switch member 25 of the switch 22 is rotated the circuit of the other two lamps is alternately made and broken. By this 25 construction, one, two, or three of the lamps may be lighted, as desired. Thus, by turning the switch 22 off and the switch 21 on, one of the lamps will be lighted; by turning the switch 21 off and the switch 22 on, two of 30 the lamps will be lighted; and by turning both of the switches on all three of the lamps will be lighted.

The pawl mechanism 28 is so constructed that each actuation of the pull chain 29 35 will cause a quarter revolution of the switch member 25. This quarter revolution will change the switch from the "off" to the "on" position, or vice versa; that is, it will move the contact member 33 out of engagement 40 with the spring contact 26 and permit the spring contact to snap down off the rear edge of the contact 33, or it will move the insulating portion 31 out of engagement with the spring contact 26 and permit the 45 spring contact 26 to snap down off the insulating portion into engagement with the contact portion 33.

While I have shown but one embodiment of my invention, it may be embodied in 50 other forms coming within the definition of the appended claims.

I claim as new and desire to secure by Letters Patent:

1. An electric stand lamp comprising an 55 insulating base having upper and lower faces, a stand for supporting said base, a plurality of lamp receptacles supported underneath and by said base, binding terminals supported on the upper face of said base, and electrical connections from said binding terminals to the contacts of said receptacles extending through said base.

2. An electric stand lamp comprising an 60 insulating base having upper and lower faces, a stand for supporting said base, a

plurality of lamp receptacles supported underneath and by said base, binding terminals supported on the upper face of said base, and electrical connections from said binding terminals to the contacts of said receptacles extending through said base, said base having a central opening through which the feed wires may be led from the lower side of the base to the binding terminals on the upper face. 70

3. An electric stand lamp comprising an insulating base having upper and lower faces, a stand for supporting said base, a plurality of lamp receptacles supported underneath and by said base, binding terminals supported on the upper face of said base, and electrical connections from said binding terminals to the contacts of said receptacles extending through said base, said stand comprising a vertical tubular central 80 supporting member under said base, said base having a central opening registering with said tubular member, whereby the feed wires may be led up through said tubular member and opening to the binding 90 terminals on the upper face.

4. An electric stand lamp comprising an insulating base having upper and lower faces, a stand for supporting said base, a plurality of lamp receptacles supported underneath and by said base, binding terminals supported on the upper face of said base, electrical connections from said binding terminals to the contacts of said receptacles extending through said base, and 100 a housing for inclosing said base, binding terminals, and the contacts of said receptacles.

5. An electric stand lamp comprising an insulating base having upper and lower 105 faces, a stand for supporting said base, a plurality of lamp receptacles supported underneath and by said base, binding terminals supported on the upper face of said base, electrical connections from said binding terminals to the contacts of said receptacles extending through said base, and a housing for inclosing said base, binding terminals, and the contacts of said receptacles, said housing comprising a removable cover 110 extending over the upper face of the base.

6. An electric stand lamp comprising an insulating base having upper and lower faces, a stand for supporting said base, a plurality of lamp receptacles supported underneath and by said base, binding terminals supported on the upper face of said base, electrical connections from said binding terminals to the contacts of said receptacles extending through said base, and a removable cover 120 extending over the upper face of the base for housing the binding terminals.

7. An electric stand lamp comprising an insulating base having upper and lower 130

faces, a stand for supporting said base, a plurality of lamp receptacles supported underneath and by said base, binding terminals supported on the upper face of said base, 5 electrical connections from said binding terminals to the contacts of said receptacles extending through said base; a removable cap having a central opening therein extending over the upper face of the base for housing 10 the binding terminals, and shade-supporting means comprising a central support extending upwardly from said base through said opening.

8. An electric stand lamp comprising an insulating base having upper and lower faces, a stand for supporting said base, a plurality of lamp receptacles supported underneath and by said base, binding terminals supported on the upper face of said base, 15 electrical connections from said binding terminals to the contacts of said receptacles extending through said base, a removable cap having a central opening therein extending over the upper face of the base for housing 20 the binding terminals, shade-supporting means comprising a central support extending upwardly from said base through said opening, and means for holding said cap in place comprising a sleeve surrounding said 25 central support and bearing on said cap and a nut threaded on said central support and bearing on said sleeve.

9. An electric stand lamp comprising an insulating base having upper and lower 30 faces, a stand for supporting said base, a plurality of lamp receptacles supported underneath and by said base, binding terminals supported on the upper face of said base, electrical connections from said binding terminals to the contacts of said receptacles 35 extending through said base, a removable cap having a central opening therein extending over the upper face of the base for housing the binding terminals, shade-supporting means comprising a central support extending upwardly from said base through said opening, and means for holding said cap in place comprising a sleeve surrounding said central support and bearing on said 40 cap and a nut threaded on said central support and bearing on said sleeve, said shade-supporting means comprising also a shade-supporting member clamped between said nut and sleeve.

10. An electric stand lamp comprising an insulating base having upper and lower faces, a stand for supporting said base, a plurality of lamp receptacles supported underneath said base, binding terminals supported on the upper face of said base, electrical connections from said binding terminals to the contacts of said receptacles extending through said base, said base having a central recess in its upper face, and a tubular internally-threaded member having an 60 65

opening in its side, non-rotatably mounted in said recess, said base having a central opening in communication with said recess, said stand comprising a vertical tubular member extending into said opening and threaded into said internally-threaded member, whereby the feed wires may be led up through said tubular members and through the opening in said internally-threaded member to the binding terminals. 70 75

11. An electric stand lamp comprising an insulating base having upper and lower faces, a stand for supporting said base, a plurality of lamp receptacles supported underneath and by said base, said base having 80 recesses in its upper face, binding terminals in said recesses, electrical connections from said binding terminals to the contacts of said receptacles extending through said base, and a flat insulating cover extending across the 85 upper face of said base for housing said binding terminals.

12. An electric stand lamp comprising an insulating base having upper and lower faces, a stand for supporting said base, a 90 plurality of lamp receptacles supported underneath and by said base, said base having recesses in its upper face, binding terminals and switch mechanism located in said recesses, electrical connections from said binding terminals and switch mechanism to the contacts of said receptacles extending through said base, and a flat insulating cover 95 extending across the upper face of said base for housing said binding terminals and switch mechanism.

13. An electric stand lamp comprising an insulating base having upper and lower faces, a stand for supporting said base, a plurality of lamp receptacles supported 105 underneath and by said base, said base having recesses in its upper face, binding terminals in said recesses, electrical connections from said binding terminals to the contacts of said receptacles extending through said base, and a flat insulating cover 110 extending across the upper face of said base for housing said binding terminals, said base having a central opening through which the feed wires may be led from the lower side of 115 the base to the binding terminals.

14. An electric stand lamp comprising an insulating base having upper and lower faces, a stand for supporting said base, a plurality of lamp receptacles supported underneath said base, binding terminals supported on the upper face of said base, and electrical connections from said binding terminals to the contacts of said receptacles extending through said base, said electrical 120 connections also serving to mechanically hold the contacts on the base. 125

15. An electric stand lamp comprising an insulating base having upper and lower faces, a stand for supporting said base, a 130

plurality of lamp receptacles supported underneath said base, binding terminals supported on the upper face of said base, and electrical connections from said binding terminals to the contacts of said receptacles extending through said base, said electrical connections also serving to mechanically hold the contacts on the base and comprising screws extending through openings in said base.

16. An electric stand lamp comprising an insulating base having upper and lower faces, a stand for supporting said base, a plurality of lamp receptacles supported underneath said base, binding terminals supported on the upper face of said base, and electrical connections from said binding terminals to the contacts of said receptacles extending through said base, said electrical connections also serving to mechanically hold the contacts on the base, and comprising screws extending through openings in said base, said lamp contacts comprising threaded shell contacts having integral ears through which said screws extend.

17. An electric stand lamp comprising an insulating base having upper and lower faces, a stand for supporting said base, a plurality of lamp receptacles supported underneath said base, binding terminals supported on the upper face of said base, electrical connections from said binding terminals to the contacts of said receptacles extending through said base, said base having a central recess in its upper face, a tubular internally-threaded member having an opening in its side, non-rotatably mounted in said recess, said base having a central opening in communication with said recess, said stand comprising a vertical tubular member extending into said opening and threaded into said internally-threaded member, whereby the feed wires may be led up through said tubular members and through the opening in said internally-threaded member to the binding terminals, and shade-supporting means comprising a post screwed into said internally-threaded member and extending above said base.

18. An electric stand lamp comprising an insulating base having upper and lower faces, a stand for supporting said base, a plurality of lamp receptacles supported underneath said base, binding terminals supported on the upper face of said base, electrical connections from said binding terminals to the contacts of said receptacles extending through said base, said stand comprising a vertical tubular central supporting member under said base, said base having a central opening registering with said tubular member, whereby the feed wires may be led up through said tubular member and opening to the binding terminals on the upper face, and shade-supporting means com-

prising a vertical member secured to said tubular member and extending above said base.

19. A switch mechanism comprising an insulating support, two switch devices supported thereby, each comprising a shaft of conducting material and a rotatable member mounted on said shaft to rotate about the axis thereof, a binding terminal electrically connected with one of said shafts, means electrically connecting said shafts, and means whereby as said rotatable members are rotated the circuits controlled thereby are made and broken.

20. An electric stand lamp comprising an insulating base having upper and lower faces, a stand for supporting said base, a plurality of lamp receptacles supported underneath said base, binding terminals supported on the upper face of said base, electrical connections from said binding terminals to the contacts of said receptacles extending through said base, said stand comprising a vertical tubular central supporting member under said base, said base having a central opening registering with said tubular member, whereby the feed wires may be led up through said tubular member and opening to the binding terminals on the upper face, and a housing for inclosing the contacts of the receptacles comprising a dished sheet-metal member having an opening through which said tubular member extends.

21. An electric stand lamp comprising an insulating base having upper and lower faces, a stand for supporting said base, a plurality of lamp receptacles supported underneath said base, binding terminals supported on the upper face of said base, electrical connections from said binding terminals to the contacts of said receptacles extending through said base, said stand comprising a vertical tubular central supporting member under said base, said base having a central opening registering with said tubular member, whereby the feed wires may be led up through said tubular member and opening to the binding terminals on the upper face, a housing for inclosing the contacts of the receptacles comprising a dished sheet-metal member having an opening through which said tubular member extends, and a spacing sleeve surrounding said tubular member between said sheet-metal member and said base.

22. A pull switch device comprising a pull switch, a flexible pull switch member, and a sheet-metal casing member having an opening through which said flexible member extends, said casing having a portion on one side of the opening adjacent the edge of the opening bent outwardly, and a portion on the opposite side of the opening adjacent the edge bent inwardly, said bent por-

70

130

tions providing a smooth bearing for the flexible pull member.

23. A pull switch device comprising a pull switch, a flexible pull switch member, and a sheet-metal casing member having an opening through which said flexible member extends, said casing having a portion on one side of the opening adjacent the edge of the opening bent outwardly, and a portion on the opposite side of the opening adjacent the edge bent inwardly, said bent portions providing a smooth bearing for the flexible pull member, the shape of the opening being such that the edges would be spaced apart if the outwardly-bent portion were bent in and the inwardly-bent portion were bent out until such portions were substantially in the same plane.

24. A finishing nut for the upper end of the shade-supporting post of a stand-lamp, comprising an annular internally-threaded member for screwing on the post, and an inverted cup-shaped sheet-metal member having its lower edge flanged over the lower edge of said annular member, and an inwardly-extending annular bead above said annular member for holding said annular member in place.

25. A switch mechanism comprising an insulating support, two switch devices supported thereby, each comprising a shaft of conducting material and a rotatable member mounted on said shaft to rotate about the axis thereof, a binding terminal electrically connected with one of said shafts, means electrically connecting said shafts, and means whereby as said rotatable members are rotated the circuit is made and broken, said shafts having their ends bent to extend laterally with respect to the axis

of said shafts, respectively, and said connecting means comprising a conductor having portions wrapped around said ends.

26. A pedestal lamp comprising an insulating base, a pedestal for supporting said base located underneath said base and centrally with respect thereto, lamp contacts supported by said base, and a housing for said lamp contacts comprising a bowl-shaped member located underneath said base and centrally with respect thereto and having an opening through which said pedestal extends.

27. A pedestal lamp comprising an insulating base having a central opening therethrough, a tubular pedestal for supporting said base located underneath said base and centrally with respect thereto, said pedestal having a portion extending into said opening, lamp contacts supported by said base, on the lower side thereof, binding terminals supported by said base on the upper side thereof and accessible to conductors leading through the pedestal and opening, and electrical connection between said binding terminals and lamp contacts.

28. A pedestal lamp comprising an insulating base, a pedestal for supporting said base located underneath said base and centrally with respect thereto, center lamp contacts supported by said base and located underneath said base, a bowl-shaped housing for said contacts located underneath said base, said bowl-shaped housing having a plurality of openings therein, and shell lamp contacts extending through said openings.

In witness whereof I have hereunto subscribed my name.

REUBEN B. BENJAMIN.
